Inventor

Samuel L. Hill

UNITED STATES PATENT OFFICE.

SAMUEL L. HILL, OF NEW YORK, N. Y., ASSIGNOR TO HIMSELF, A. PALMER, AND A. S. DOANE, OF SAME PLACE.

SPELLING-BLOCK.

Specification forming part of Letters Patent No. 21,798, dated October 12, 1858; Reissued March 26, 1867, No. 2,528.

To all whom it may concern:

Be it known that I, SAMUEL L. HILL, of New York, in the county and State of New York, have invented a new and Improved 5 Spelling-Block; and I do hereby declare the following to be a full and exact description of the same, reference being had to the accompanying drawings, forming part of this specification.

10 Figure I represents three sides of a block of one set, in which are seen two letters of the alphabet (*a*, *b*), and the numerical figure, (*c*). Fig. II shows the remaining three sides of the same block, with three other 15 letters of the alphabet, (*d*, *e*, *f*). Fig. III. In this drawing, three sides of a block of the second series appear, (*a'*, *b'*) with two letters of the alphabet and the numerical figure (*c'*). Fig. IV. The remaining three 20 sides of the same block are shown and upon it three letters of the alphabet, (*a'*, *e'*, *f'*).

The nature of my invention consists in preparing a series of wooden blocks, of any required number each block having placed 25 upon it certain letters of the alphabet, for the purpose of spelling.

The object of my invention, is to place in the hands of children a useful and instructing recreation.

30 To enable others to make and use my invention I will proceed to describe it.

I provide a series of six-sided wooden blocks; these blocks are divided into two sets, distinguished from each other by color. 35 The blocks in each set are numbered 1, 2, 3, 4, 5, 6, 7, 8, 9, 0 respectively, and when more blocks are used, as is sometimes the case, the numbers are increased in proportion. On five sides of each block, five letters of the

alphabet are placed, care being taken that 40 the same letter shall not occur twice on the same block, and on the sixth side, the numerical figure first referred to. The numerical figure serves by the aid of the printed key, to show on what block any desired 45 letter or letters will be found. The set of blocks being thus formed and reference being had to the printed key and numerical figure, it will be found that words can be 50 readily spelled, and those in which the same letter occurs twice which was not done and could not be done with the old style of blocks or those now in use. Thus the word "dog" could be spelled with the old style, but the word "goose" or any other word in 55 which the same letter occurred twice could not be. I also consider my mode of constructing the blocks, decidedly superior to the old style, in which the letters were first printed on paper and then pasted upon the 60 block, thus rendering them easy to be torn off and destroyed, whereas by the mode I employ, of placing the letters directly upon the block itself, by painting them upon it, this is guarded against.

Having thus described my invention what I consider as new and desire to secure by Letters Patent is—

1. I claim the arrangement of letters on any number of six sided blocks, in the manner described and for the purpose specified.

2. I claim giving to and placing upon each block its proper numerical figure, for the purpose specified.

SAMUEL L. HILL.
